US00D690888S

(12) **United States Design Patent**
Pearson et al.

(10) **Patent No.:** **US D690,888 S**
(45) **Date of Patent:** **** Oct. 1, 2013**

(54) **FLUID EXTRACTION TOOL**

(75) Inventors: **Dan Pearson**, Englewood, CO (US);
Adam Dean Bearup, Lakewood, CO (US); **Eric Lynn Shark**, Littleton, CO (US); **Nathan Hammer**, Centennial, CO (US); **Richard James Couch**, Denver, CO (US); **Al Jesse Varney**, Denver, CO (US)

(73) Assignee: **Karcher North America, Inc.**, Englewood, CO (US)

(**) Term: **14 Years**

(21) Appl. No.: **29/424,138**

(22) Filed: **Jun. 7, 2012**

(51) LOC (9) Cl. **15-05**

(52) U.S. Cl.

USPC **D32/32**

(57) **CLAIM**

The ornamental design for a fluid extraction tool, as shown and described.

DESCRIPTION

FIG. 1 is a front perspective view of a fluid extraction tool showing our new design;

FIG. 2 is a top plan view thereof;

FIG. 3 is a front elevation view thereof;

FIG. 4 is a right side elevation view thereof;

FIG. 5 is a left side elevation view thereof;

FIG. 6 is a rear elevation view thereof; and,

FIG. 7 is a bottom plan view thereof.

The broken lines showing a fluid extraction tool are for the purpose of illustrating environment and form no part of the claimed design.

1 Claim, 6 Drawing Sheets
